SAMUEL W. HUNTINGTON, OF AUGUSTA, MAINE.

Letters Patent No. 70,571, dated November 5, 1867.

IMPROVED BOOT-BLACKING AND POLISHING MACHINE.

The Schedule referred to in these Letters Patent and making part of the same.

TO ALL TO WHOM THESE PRESENTS SHALL COME:

Be it known that I, SAMUEL W. HUNTINGTON, of Augusta, in the county of Kennebec, and State of Maine, have invented a new and useful Machine for Dressing, Cleaning, Blacking, and Polishing Boots or Shoes; and do hereby declare the following to be a full, clear, and exact description of the same, due reference being had to the accompanying drawings, making part of this specification, and in which—

Figure 1 is a front elevation,

Figure 2 a vertical and transverse section of my invention.

The object of my present invention is to construct a compact and portable machine for dressing and finishing boots or shoes during process of manufacture, as well as for cleaning, blacking, and polishing boots or shoes as now practised by hand.

The invention consists in two revolving brushes applied to and carried by a shaft, properly supported upon a table, and operated by a treadle or other means for putting them in rapid rotation, one of the revolving brushes being provided with an adjustable trough for containing the dressing or blacking material, substantially as hereinafter described.

In the drawings above mentioned, the table or stand of the machine is shown as composed of a frame, A, and table B, properly constructed for supporting the operative parts of the machine. The two cylindrical brushes are shown at C D, as fixed to a horizontal shaft, a, supported at its ends in standards b b, rising from the table B, a pulley, c, being fixed to the shaft a, at or near one end thereof, around which is a driving-pulley, d, supported in a bearing, e, fixed to a cross-bar, f, of the frame A, and an endless belt, g, travelling, and putting the brushes in revolution. A crank, h, and treadle i are combined with the pulley d for actuating such pulley. A crescent or segmental-shaped trough, or box, j, is disposed below the brush C, and in such manner that the periphery of the brush shall dip slightly into or touch the contents of such trough, for the purpose of supplying the brush with dressing or blacking material, as the case may be, the vertical adjustment of the trough j being regulated, as its contents diminish in quantity, by a screw, k, which is screwed through the table A, and against the under side of a lip, l, fixed to the outer end of the trough, as represented. The inner end of the trough is hinged to the "back-board" of the table A in such manner as to allow of its ready removal or detachment therefrom, as its contents may become exhausted. As the contents of the trough are taken up and applied by the brush C, the screw k is to be elevated and the trough raised, to compensate for this lowering of the material. When the contents of the box are exhausted, it is to be removed, and a full one substituted. For convenience in this respect, I construct a box, as shown in fig. 3 of the drawings, as of the shape in vertical section of the segment of a circle, and with a cover, m, for safety in transportation. A small hook, n, is affixed to one end of the box, for attachment to the back-board of the table. As a means of convenience, I combine with the brushes C and D, a grindstone, D', affixed to the shaft a, as shown in the drawings.

In operating with the above-described machine, the box containing the dressing or blacking material, as the case may be, is affixed in position, as shown in the drawings. If the object is to finish or dress a new boot, such boot is held in contact with the brush C, while in revolution, which applies to the boot the gum-tragacanth material, if it should be necessary. If the object is to black and polish an old boot, or one being worn, the periphery of the brush C is to be dampened by any proper means which will dilute the blacking adhering to the brush. The boot is then to be held in contact with the revolving brush, and manipulated until all parts of it are supplied with blacking, when it is to be subjected to the action of the second or polishing-brush, which instantly imparts a high polish to it, the current of air induced by the rapid revolution of the brush tending not only to hasten the drying of the blacking, but to impart a peculiarly soft lustre to the surface of the boot or shoe. The whole operation of blacking and polishing a boot is performed in a very short space of time.

The use heretofore of machines for blacking boots and shoes has been restricted, owing to their expense, to hotels, steamboats, etc. As my machine may be manufactured at a very reasonable cost, it becomes available to families and individuals. I would remark that a vertical or horizontal sliding motion may be imparted to the brushes C and D, instead of a rotary one. The latter mode, however, affords the cheapest construction, and will be found preferable.

Having described my invention, what I claim, and desire to secure by Letters Patent, is—

The combination in a machine, such as described, with one or more rotating brushes, of an adjustable trough or blacking-receptacle, substantially in the manner and for the purposes herein shown and set forth.

Witnesses:

EDWARD GRIFFITH,
FREDERICK CURTIS.
